REFRIGERATOR DRIP PAN

Herman J. Strobush, George H. Platten, and Donald Swanson, St. Paul, Minn., assignors to Seeger Refrigerator Company, St. Paul, Minn., a corporation of Minnesota

Application September 20, 1937, Serial No. 164,742

3 Claims. (Cl. 62—99)

Our invention relates to an improvement in drip pans for refrigerator cases of a type designed to catch dropping condensed moisture from the evaporator coils of the case.

5 It is a well-known fact that where refrigerator coils are positioned within a refrigerator body adapted to contain foods of various sorts, the evaporator coil will accumulate moisture in the form of frost on the coil. When this coil or the 10 surrounding air is permitted to heat to some extent, this frost will melt. The melting of this frost causes moisture to drop from the coils which may readily injure or spoil food within the refrigerator cabinet. Attempts have been made to 15 catch this moisture, but such attempts have usually resulted in constructions which seriously impair the circulation of air about the coil. The usual type of refrigerator drip pan extends continuously beneath the coil, thus necessitating all 20 air currents to travel about the sides of this pan.

Difficulty has also been experienced with condensation on the drip pan itself. The air cooled by the refrigerated coil has of course a tendency to move downwardly, and therefore will contact 25 the upper surface of the drip pan. As this cold air is prevented from moving directly downwardly into contact with the air beneath the pan, this air on the under surface of the pan is often considerably warmer than the air above the pan, this 30 difference in temperature condensing the moisture in the warmer air upon the bottom of the pan. Accordingly, while the drip pan prevents the melted frost from dropping onto the food within the refrigerator, condensation often drops 35 from the drip pan onto the foodstuffs.

It is a purpose of our invention to provide an inclined drip pan formed in separate units, each 40 unit of which is secured beneath one or a series of evaporator coils. Each unit is provided with a drain pipe, which may lead to a suitable outlet from the refrigerator case. The drip pans extend only substantially the width of the refrigerator evaporator coil and support, and by spacing the 45 rows of the coil properly, sufficient space is provided between the drip pans to permit the free passage of air therebetween. By this construction the air need not travel a substantial distance in a horizontal direction before being permitted to move downwardly within the case.

50 It is a further object of our invention to provide a drip pan formed of a plurality of members secured together. These members are spaced one from the other to provide a space therebetween for insulating purposes. This construction prevents the warmer air from contacting the lower

surface of the drip pan, which is on one side subjected to air cooled by the evaporating coil, and thus prevent condensation on this drip pan.

It is a further feature of our invention to provide an insulated drip pan which may be insulated either by providing two spaced metallic members having an air space therebetween, two spaced metallic members having insulation therebetween or a coating of insulation attached directly to the outer surface of the drip pan. Any 5 of these constructions will prevent direct contact between the outer or under surface of the drip pan and heated air, and will therefore prevent condensation on the drip pan.

It is an additional feature of our invention to 15 provide an evaporating coil formed of a series of loops of tubular piping placed either directly one above the other or else offset one above the other. These superimposed coils are connected by integral cooling fins closely spaced throughout the 20 length of the coil. These cooling fins connect the various coils integrally together and form a greater cooling area than could otherwise be accomplished.

These and other objects and novel features of 25 our invention will be more clearly and fully set forth in the following specification and claims.

In the drawings forming a part of our specification:

Figure 1 is a cross-sectional view through a 30 refrigerator cabinet and through a drip pan illustrating the construction thereof.

Figure 2 is a bottom plan view diagrammatically illustrating the position of the coil within the refrigerator case.

Figure 3 is a cross-sectional view through a 35 slightly different form of drip pan from that illustrated in Figure 1.

Figure 4 is a sectional view on the line 4—4 of Figure 1, illustrating the coil construction.

Figure 5 is a cross-sectional view through a 40 refrigerator case, illustrating a slightly different form of construction of drip pan.

Figure 6 is a cross-sectional view illustrating 45 still another modified form of drip pan construction.

The refrigerator case A may be of any desired type, the case illustrated being used as a display case for meat or other foodstuffs. The display case A is illustrated as having display windows 50 10 supported in spaced relationship within the frame 11 and a door aperture 12 is provided in the opposite side of the case.

Spaced longitudinally along the length of the refrigerator case, we provide hangers 13 which 55

depend from the top 14 of the case and which are substantially J-shaped, having a horizontally extending flange 15 at the bottom of the depending hanger, and an upwardly extending retaining flange 16 extending upwardly from the end of the flange 15 parallel to the vertically extending depending portion 17. These hangers 13 support the evaporating coil 19 by extending between the radiating fins 20 attached to the coil 19. As illustrated in Figure 4 of the drawings, the fins 20 are spaced at short intervals throughout the length of the tube or coil 19 and are in the form illustrated in Figure 1 substantially rectangular in shape. The coil 19 is formed of a single length 15 of tube bent to form superimposed loops 21 and the fins 20 are secured to each of the loops 21. The lower edge of some of the cooling fins 20 rest upon the horizontally extending portion 15 of the hangers 13 to support the coil in place.

Underneath each of the parallel sides of the loops 21 we provide a drip tray B. The tray B or pan is formed with a pan member 23 having a horizontal portion 24 extending beneath the coil 19. On one side of the horizontal portion 25 the drip pan extends upwardly at 25 along the outer surface of the hangers 13 and is provided at the top with a horizontally extending sealing flange 26. The flange 26 interlocks with the flange 27 on a pan covering 28 which extends downwardly at 29 parallel to the portion 25 of the tray 23 and extends horizontally at 30 terminating in an upwardly extending flange 31 which interlocks with an edge 32 of the horizontal portion 24 of the tray 23. In other words, a double 35 wall metallic tray is provided with a space therebetween. As illustrated on the left side of Figure 1 of the drawings, the space between the tray 23 and the outer tray covering 28 may be filled with insulation 32 or this space may be unfilled as illustrated on the right side of Figure 1, the air between the tray and the tray covering forming the insulation therebetween.

Drain members 33 extend downwardly from the tray 23 and are connected by a suitable drain 45 pipe 33' to an outlet for the condensed moisture. A deflector or baffle plate 34 supported by a cross strip 35 extends beneath the portion of the coil 19 connecting the parallel lengths of the loop to deflect any moisture dropping from these portions of the coil into the drip pan B.

In Figure 3 of the drawings, we disclose a drain pan 36 having a flange 37 thereupon adapted to extend up parallel the vertical portion 17 of the hanger 13 and having a horizontally extending flange 39 at the top of the same. The opposite edge of the tray 36 extends upwardly at 40 and is folded down at 41. Insulation 42 is secured to the tray 36 bounded by the transversely extending flange 39 and the vertically extending flange 41. This insulation 42 prevents heated air from contacting the lower surface of the tray 36 and thereby prevents condensation on this tray.

Figure 5 illustrates a construction which is 65 slightly different from that illustrated in Figure 1 in detail construction. In this type of construction D the tray 43 is provided with a substantially horizontally extending portion 44 having a guard flange 45 extending angularly and 70 upwardly therefrom. The flange 45 is bent downwardly to provide a vertical edge flange 46 by means of which the tray 43 is attached to the spaced tray covering 47. On the opposite side of the horizontal portion 44, the tray 43 inclines 75 upwardly at 49 and then extends vertically in

spaced relation to the hangers 13 terminating in a transverse flange 51. Clips 52 extend between the vertically extending flanges 50 and the hangers 13 and bolts 53 extend through the hangers 13, the clips 52, through spacing washers 54 and the flanges 50, these latter members being held in place by means of a wing nut 55. Nuts 56 on the bolt 53 hold the bolt in place on the hangers 13 even when the pans 43 have been removed.

The cover trays 47 follow the same general 10 contour as the pan 43 and are provided with an upwardly extending flange 57 to which flange 46 of the pan 43 may be bolted. The fastening bolts 59 extend through spacing washers 60 which hold the flanges 57 spaced from the flanges 43. The tray covering members 47 are also attached to the pan 43 by bolts 61 extending through spacing washers 62 and through the inclined portion 49 of the pan 43. Drain pipes 63 extend downwardly from the pan 43 for connection with drain pipes 64.

The drip pans may also be of the form illustrated in Figure 6 of the drawings. In this construction, the coil 65 extends through bifurcated fins 66 which are integrally secured to the various convolutions of the coil 65, supporting the coil 65 in two parallel rows. The drain pan E is supported by the hangers 67 secured to the top of the refrigerator casing and acting to support the coil 65 by engagement with the outer and lower surfaces of the fins 66. The drain pan E is in the form of a trough-shaped member 69 having an upwardly extending side 70 thereupon to extend parallel the hangers 67. Bolts 71 extend through this upwardly extending portion 70, and the hangers 67, spacing washers 72 being interposed between the portion 70 and the hangers 67. Wing nuts 73 on the bolts 71 hold the drip pan E in place.

The trough-shaped portion 69, and the upwardly extending side 70 are provided with metallic coverings 74 and 75 which cover the core of insulation. Drain pipes 76 extend downwardly from the trough-shaped portions 69 which are connected by piping 77 to a suitable outlet drain pipe 79.

It may be seen that any moisture freezing upon the coil or upon the fins connecting the coils will run down the fins and drip off into the drip pan. The upper surface of the drip pans are exceedingly cold as they are closely adjacent the refrigerating coils. The air beneath the pans is at a considerably warmer temperature but this air cannot contact the lower surface of the pan directly because of the insulation between the spaced pad and covering.

In accordance with the patent statutes, we have described the principles of construction of our refrigerator drip pan, and while we have endeavored to set forth the best embodiment thereof, we desire to have it understood that this is only illustrative of a means of carrying out our invention, and that obvious changes may be made within the scope of the following claims without departing from the spirit of our invention.

We claim:

1. In a refrigerator case, an elongated cooling coil, means securing said coil to said refrigerator case a pair of spaced parallel baffles extending beneath said coil, each of said baffles comprising an upper and a lower plate member in spaced relation with corresponding portions substantially parallel, a side plate extending upwardly from said upper plate in spaced relation to the

cooling coil, a spacer between said side plate and said coil, and means independent of said coil securing means securing said side plate directly to said coil, said lower plate member including 5 a second side plate extending upwardly in spaced relation to said first named side plate.

2. In a refrigerating case, an elongated coil, a pair of spaced parallel baffles extending beneath said coil, each of said baffles including an upper 10 and a lower plate member in spaced relation with corresponding portions substantially parallel, the upper plate member being bent to provide a raised portion terminating in a depending flange, means securing the said flange and the 15 marginal inner edge of said lower plate member together, an upwardly extending side plate on said upper plate member extending in spaced relation to the coil, spacer means between said side plate and said coil, and securing means securing 20 said side plate to said coil, said lower plate member including a second side plate extending upwardly in spaced relation to said first named side plate.

3. In a refrigerator case, an elongated coil,

a pair of spaced parallel baffles inclined from one end toward the other extending beneath said coil, each of said baffles including an upper and a lower plate member in spaced relation with corresponding portions substantially parallel, the 5 upper plate member being bent to provide a raised portion terminating in a depending flange, means securing the said flange and the marginal inner edge of said lower plate member together, an upwardly extending side plate on said upper 10 plate member extending in spaced relation to the coil, and securing means securing said side plate to said coil, said lower plate member including a second side plate extending upwardly in spaced relation to said first named side plate, 15 drain pipes extending downwardly from the lower end of said baffles, and means connecting said drain pipes with a common drain to conduct liquid to said common drain.
